SAMUEL A. McCONNELL AND BEN ERICKSON, OF PORTLAND, OREGON.

SWITCH CONTROL.

1,089,850.

Specification of Letters Patent. Patented Mar. 10, 1914.

Application filed August 26, 1912. Serial No. 717,034.

To all whom it may concern:

Be it known that we, SAMUEL A. McCONNELL and BEN ERICKSON, citizens of the United States, residing at Portland, in the 5 county of Multnomah and State of Oregon, have invented certain new and useful Improvements in Switch Controls, of which the following is a specification.

The present invention pertains to mechanism for controlling electric switches of the form employed in operating electric motors and has for its object to provide a device which will hold the lever from accidental engagement with the binding posts, and 10 which also will render it impossible to throw the full current used in starting the machine through the smaller fuses, which fuses would not sustain the large current. We accomplish this object by the mechanism illustrated in the accompanying drawing, in 15 which—

Figure 1 is a plan view of a switch showing our improved switch control applied thereto. Fig. 2 is a side elevation of same. 20 Referring to the drawing in detail, 1 represents the base of the usual three blade knife switch, having the handle 2 fixed upon the cross bar 3, by means of which the knife blades are operated in the usual and well 25 known manner.

Intermediate two of the rows of switch terminals is arranged a switch control, consisting of an upright member 4 formed of sheet metal, the lower end 8 of which is 30 bent at right angles thereto to form a base or support, which is fixed to the base 1 on the line of the pivotal supports of the switch lever. At the upper end of the standard 4 is formed an arched portion 5 each end of 35 which approaches the level of the switch terminals at its respective side and the arch is formed on such a radius that it will be freely cleared by the cross bar 3, of the switch lever.

40 A short distance above one end of the arch is a transverse bend forming the shoulder 7, from which point to the tip the arched member is inclined to a point some distance beyond the plane of the arch 5 and the support 4. At an equal distance from the opposite end of the arch another shoulder 7^a is 45 similarly formed, but extending in the opposite direction from shoulder 7, and the terminal portion 6^a is formed similar to terminal 6, but it also is inclined in a direction 50 opposite to that of the latter.

Upon the cross bar 3 is secured a bracket or clip 13 held in place by the screw 14, and from which is supported a bar 15 which depends sufficiently to bear against the side 60 of the arch 5, as the lever is operated. The bracket will be fixed in line with the arch and as the lever is swung forward from either set of switch terminals the bar will engage the rounded face of the arch terminal, which stands a sufficient distance above the switch terminals that the switch will always be open before the lever engages the arch. The lever will stand, in inoperative position, between the shoulders 7 and 7^a as indicated in dotted lines at 2', and it may be engaged in a spring clip 12, which will more securely prevent movement thereof, that might result in accidental closing of the switch. 75

In starting the machine, it will be noted that the lever cannot be thrown back to the switch terminals *a* because of the shoulder 7, but it must be thrown forward to the switch terminals *b* which connect with the starting fuses located in the panel box, in any convenient location. These fuses are made large so as to withstand the large current of electricity required in starting the machine, after which the lever can be 80 thrown into engagement with the switch terminals *a*, the bar 15, engaging the rounded face of the terminal 6^a, whence it passes the shoulder 7^a and moves unobstructed to its destination. To these latter switch terminals are directly connected the running fuses which are adapted to carry the weaker current needed in operating the machinery. If the lever were placed in contact with the switch terminals *a* at the start the heavy 85 strain would result in destroying the running fuses. The base flange 8 is pivotally secured upon the base 1 of the switch by means of the screw 9 at one end thereof; and at the other end is formed a transverse slot 90 100 through which a set screw 11 passes to engage in the base 1. By this means the arch may be shifted so as to bring it into proper alignment for engagement with the bar. 105

Having thus described our invention what we claim as new and desire to secure by Letters Patent is—

1. A switch control comprising in combination an oscillating switch lever, an ar- 110 cuate member supported at the center of oscillation of the switch lever, a pin depend-

ing from the cross bar of the lever and adapted to bear against the arcuate member, and a laterally offset terminal portion at each end of the arcuate member to form 5 stops for the depending pin, the terminal portion at one end being offset from the body portion in an opposite direction to the terminal portion at the other end, and inclining from its respective shoulder to a 10 point across and beyond the plane of said member.

2. A switch control comprising in combination an oscillating switch lever, an arcuate member supported at the center of 15 oscillation of the switch lever, a pin depending from the cross bar of the lever and adapted to bear against the arcuate member, a laterally offset terminal portion at each end of the arcuate member to form 20 stops for the depending pin, the terminal portion at one end being offset from the body portion in an opposite direction to the terminal portion at the other end, each terminal portion inclining from its respective 25 shoulder to a point across and beyond the plane of said member, and means for adjusting the alinement of the arcuate member.

3. A switch control comprising in combination an oscillating switch lever, an arcuate member supported at the center of 30 oscillation of the switch lever, a pin depending from the cross bar of the lever and adapted to bear against the arcuate member, a laterally offset terminal portion at each end of the arcuate member to form 35 stops for the depending pin, the terminal portion at one end being offset from the body portion in an opposite direction to the terminal portion at the other end, each 40 terminal portion inclining from its respective shoulder to a point across and beyond the plane of said member, means for adjusting the alinement of the arcuate member and means at the intermediate portion of the arcuate member for releasably engaging the depending bar.

In testimony whereof we affix our signatures in presence of two witnesses.

SAMUEL A. McCONNELL.
BEN ERICKSON.
